CLAIM

The ornamental design for a combination electromagnetically charged ball and cradle, as shown and described.

DESCRIPTION

FIG. 1 is an exploded front perspective view of the combination electromagnetically charged ball and cradle showing our new design;

FIG. 2 is a front elevation view shown with the ball resting in the cradle;

FIG. 3 is a top plan view thereof; and,

FIG. 4 is a bottom plan view thereof.

The broken lines showing in FIGS. 1-4 are included for the purpose of illustrating a portion of the cradle portion that forms no part of the claimed design.

1 Claim, 1 Drawing Sheet
